United States Patent Office

Des. 187,596
Patented Apr. 5, 1960

187,596

TABLE

Trace S. Christenson, Jr., South Bend, and Howard B. Barber, North Manchester, Ind., assignors to Peabody Seating Company, Inc., North Manchester, Ind., a corporation of Indiana

Application November 28, 1958, Serial No. 53,566

Term of patent 14 years

(Cl. D33—14)

Fig. 1 is an end view of a table, showing our new design;

Fig. 2 is a side view of the same; and

Fig. 3 is a top plan view of the same.

The dominant features of our design reside in those portions shown in full lines on the drawing.

We claim:

The ornamental design for a table, substantially as shown and described.
